UNITED STATES PATENT OFFICE.

JOHN T. JACKSON, OF COLDWATER, MICHIGAN.

POSTER BOARD.

Application filed June 8, 1926. Serial No. 114,500.

The invention relates to poster boards upon which advertising matter is displayed, usually by pasting sheets of paper upon which the matter, pictorial, descriptive, or otherwise, is printed.

It is customary to clear the poster board at intervals, this being accomplished by means of a scraper. As ordinarily constructed the metal sheets forming the surface of the poster board overlap and are attached to the supporting structure by nails driven through the overlapped portions of the sheets. When scraping the board to remove the old bill, or advertising sheet, the 10 nails are frequently dislodged and require to be replaced and the projecting edges of the metal sheets become snagged and bent, necessitating repair.

The present invention provides a poster board of the character aforesaid presenting a smooth surface free from projecting parts, such as nail heads and overlapping edges, and which is strengthened and braced by having edge portions of the metal sheets 20 bent at a right angle, butted and attached to the supporting structure.

The invention furthermore provides sections which are attachable to the supporting structure, each of such sections consisting of a batten frame and sheet metal attached thereto, the section being preferably provided along a butting edge with an offstanding flange to overlap the joint formed between adjacent sections.

While the drawings illustrate a preferred embodiment of the invention it is to be understood that in adapting the means to meet specific needs and requirements, the design may be varied and such other changes 30 in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a perspective view of a poster board embodying the invention, parts being broken away,

Figure 2 is a rear view of a portion of the poster board, parts being broken away,

Figure 3 is a horizontal sectional view on the line 3—3 of Figure 2, and

Figure 4 is a detail perspective view of

end portions of adjacent sheets, the same being separated.

Corresponding and like parts are referred to in the following description and designated in the several views of the drawings by like reference characters.

The poster board includes a supporting structure, which, as shown comprises uprights 1, braces 1^a and stringers 2. The uprights 1 may be of any height and spaced apart a determinate distance. The surface of the poster board comprises a plurality of metal sheets which are attached to the batten frames forming sections. Usually, the uprights 1 are spaced apart a distance corresponding to the combined width of two metal sheets. Each section or panel preferably includes two metal sheets which are reinforced and strengthened by means of battens 3 and bridges 4, the latter being disposed horizontally between the battens which in practice are disposed vertically. Cleats 5 and 6 connect the bridges and uprights. The cleats 5 are nailed or otherwise secured to the intermediate battens 3^a of each section or panel and their end portions project so as to overlap the adjacent ends of the bridges 4 to which they are nailed or otherwise made fast. The cleats 6 are nailed or otherwise secured to the end battens 3 and the adjacent ends of the bridges 4. The bridges 4 are disposed upon opposite sides of the battens 3^a and between it and the battens 3. The sides of the battens and bridges facing the metal sheets come flush with and are in contact with the metal sheets, so as to strengthen and reinforce the same.

The numeral 7 designates the metal sheets which may be of any width and which usually are of a length corresponding to the height of the poster board, as shown most clearly in Figure 1. The longitudinal edge portions of the metal sheets 7 are bent in the same direction at a right angle, as indicated at 8, to form flanges which are arranged to abut, as shown most clearly in Figure 3, thereby reinforcing and strengthening the sheet, besides providing means to receive the nails, or like fastenings whereby the sheets are attached to the battens 3 and 3^a by being driven through the flanges, as indicated most clearly in Figure 3. The battens are located in the angles formed between the sheets and the bent edge por-

tions 8 thereof. An outer edge portion of a sheet of each section or panel has a portion bent outwardly, as indicated at 9, to overlap the joint formed between adjacent panels or sections. The surface of the poster board comprises panels or sections and each of the panels comprises two metal sheets 7. A batten 3^a is located at the meeting edges of the two sheets comprising a panel, and a batten 3 is located at the outer edge of the panel, as shown most clearly in Figures 2 and 3. End portions of the inner flange 8 of one of the sheets 7 of a panel are cut and project, as indicated at 10, to overlap end portions of the adjacent sheet to which they are secured and to the bridge pieces by nails or suitable fastening means, as indicated most clearly in Figure 1. After the panels have been placed in position the poster board is finished by applying a molding 11 thereto which provides a frame around the ends and the top and bottom thereof.

It will be understood from the foregoing that the poster board presents a smooth surface which is free from projecting nail heads and overlapping edge portions, hence old posters may be readily removed, without endangering the surface to such an extent as to require repair. The fastenings securing the panels or sections to the intermediate stringers 2 have their heads sunk so as to offer no projection for a scraper or like tool to catch upon when clearing the board of posters.

Having thus described the invention, I claim:

1. A poster board comprising a frame including battens, metal sheets having edge portions bent at a right angle to form flanges which are disposed to abut and en-

gage the side of a batten to which the abutting flanges are attached, one of the flanges having end portions cut and extended outwardly from the sheet substantially in the plane thereof to overlap and engage the outer side of the adjacent sheet to which they are attached.

2. A poster board panel comprising metal sheets having their longitudinal edge portions bent laterally in the same direction to provide reinforcing and attaching flanges, adjacent sheets having the inner contiguous flanges abutting, a batten disposed in the angle formed between a sheet and the said abutting flanges and having the latter secured thereto, other battens arranged in the angle formed between the outer flanges and the sheets and attached to the said flanges, bridge pieces between the battens, and means connecting oppositely disposed bridge pieces to one another and to the battens.

3. A poster board panel comprising metal sheets having their longitudinal edge portions bent laterally in the same direction to provide reinforcing and attaching flanges, adjacent sheets having the inner contiguous flanges abutting, and one of the abutting flanges having end portions cut and extended outwardly therefrom about in the plane of the panel, a batten in the angle formed between a sheet and the said abutting flanges and having the latter and the said end extensions of a flange secured thereto, other battens arranged in the angle formed between the outer flanges and the sheets and attached to the said flanges, and bridge pieces between the battens and connected thereto and to one another.

In testimony whereof I affix my signature.

JOHN T. JACKSON. [L.S.]
